CLAIM

The ornamental design for a camera handle as shown and described.

DESCRIPTION

FIG. 1 is a front, left and top perspective view of a camera handle showing our new design;

FIG. 2 is a rear, right and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of a portion labeled as 9 on FIG. 7.

The long dash-short dash broken lines depict enlargement boundaries that form no part of the claimed design. The evenly broken lines illustrate portions of the camera handle that form no part of the claimed design.

1 Claim, 9 Drawing Sheets
